LIQUID DISPENSER FOR SURFACE TREATING MACHINES

Carl Eric Sixten Andersson-Sason, Solna, Sweden, as-
signor to Aktiebolaget Elektrolux, Stockholm, Sweden,
a corporation of Sweden

Application September 20, 1954, Serial No. 32,344

Claims priority, application Sweden April 27, 1954

Term of patent 14 years

(Cl. D9—2)

Fig. 1 is a rear perspective view of a liquid dispenser for surface treating machines showing my design, and a surface treating machine which is illustrated in dotted lines for the purpose of illustration;

Fig. 2 is a side perspective view thereof;

Fig. 3 is a top plan view thereof in which only a part of the chain is illustrated and the handle of the surface treating machine is removed;

Fig. 4 is an enlarged rear perspective view of the liquid dispenser to illustrate details more clearly, the chain being shown in a coiled position;

Fig. 5 is a rear view thereof in elevation;

Fig. 6 is a side view thereof;

Fig. 7 is a top plan view; and

Fig. 8 is a front perspective view thereof in an inverted position.

In Figs. 5, 6, 7 and 8 the chain is shown broken away for convenience of illustration.

What I claim is:
The ornamental design for a liquid dispenser for surface treating machines, as shown and described.
